Primary Examiner — Jonathan J Han*Assistant Examiner* — Molly K. Orzechowski(74) Attorney, Agent, or Firm — Banner & Witcoff, Ltd.(57) CLAIM

The ornamental design for a shoe, as shown and described.

DESCRIPTION

FIG. 1 is a rear perspective view of a shoe showing my new design;
FIG. 2 is a rear view thereof; and,

FIG. 3 is an opposite side rear perspective view thereof.
The broken lines immediately adjacent to the solid line and the shaded area define the bounds of the claimed design and form no part thereof. The unshaded area forms no part of the claimed design. The even-length broken line within the shaded area represents a feature that forms no part of the claimed design. The broken lines depicting the remainder of the shoe form no part of the claimed design.
